UNITED STATES PATENT OFFICE.

RAY S. ENGLE, OF BINGHAMTON, NEW YORK.

COMBINED STAPLE AND STRAP.

Application filed August 25, 1922. Serial No. 584,293.

To all whom it may concern:

Be it known that I, RAY S. ENGLE, a citizen of the United States, residing at Binghamton, in the county of Broome and State 5 of New York, have invented certain new and useful Improvements in a Combined Staple and Strap, of which the following is a specification.

This invention relates to a novel type of 10 retaining member embodying strap and staple features.

The primary object of the invention is the provision of a simple and compact retaining member for use in connection with 15 cables, conduits and pipes, embodying an arrangement which will permit of the quick and convenient attachment of the same in a minimum of time.

A further object of this invention is the 20 provision of an improved retaining member of the above mentioned character, which is relatively economical to construct and embodies strap and staple elements which are fixedly connected in permanent manner.

Other objects and advantages of this invention will be apparent during the course 25 of the following detailed description.

In the accompanying drawing, forming a part of this specification, and wherein similar reference characters designate corresponding parts throughout the several views.

Figure 1 is a transverse cross sectional view, taken through an electrical conductor, such as an armored cable, showing the manner in which the improved device attaches 35 the same to a support.

Figure 2 is a side elevation of the details embodied in Figure 1.

Figure 3 is a plan view of the details embodied in Figure 1.

Figure 4 is a cross sectional view, showing a step in the assemblage of the parts of the improved retaining member.

Figure 5 is a cross sectional view, altogether similar to Figure 4, however, showing the manner in which the staple element of this invention is mutilated in order to provide a permanent attachment of the same with respect to the strap element, this view 60 being taken substantially on the line 5—5 of Figure 1.

Figure 6 is a perspective view of the strap element embodied in this invention.

In the drawing, wherein for the purpose 65 of illustration is shown but the preferred embodiment of this invention, the letter A

designates the improved retaining device, adapted for attachment to a support B, in order to maintain a conduit or similar device C in proper position.

Referring to the improved retaining device A, the same preferably comprises a strap member 10, which may be formed of galvanized iron, fibre, composition material, wood or the like, consistent with the use to 65 which the improved retaining member A is to be put. This strap member 10 is formed of a single piece of material, embodying the U-shaped portion 11, which includes the relatively flat legs 12 and 13 connected by an arcuate bight portion 14. The material of which the strap 11 is formed is flanged as at 15 and 16 outwardly of the edges of the legs 12 and 13 remote from the bight portion 14, these flanges 15 and 16 being disposed in a plane substantially at right angles to the planes defined by the leg portions 12 and 13. Each of the flanges 15 and 16 may have a single aperture 17 transversely therethrough. By this arrangement a pocket 18 is provided in the body 11 of the strap 10 intermediate the legs 12 and 13.

Referring to the staple element 20, the same is preferably formed of galvanized wire, or other metal or alloy, and is U-shaped in formation, including the attaching legs 21 and 22 which are connected by the arcuate head portion 23. The lower ends of the legs 21 and 22 are pointed to provide prongs 24 for biting into the material of the support B; these prongs 24 being flattened as at 25 in converging relation toward the pointed ends thereof.

In the assemblage of the staple element 20 to the strap member 10 which is effected in 95 the manufacture of the retaining devices A, the legs 21 and 22 are inserted through the apertures 17 in the strap flanges 15 and 16 so that the arcuate bite or head portion 23 of the staple 20 overlies in abutting engagement with the outer surface of the bight or head portion 14 of strap 10, as is illustrated in Figures 1, 2, and 3 of the drawing. In this arrangement, the upper portions of the staple legs 21 and 22 are in abutting engagement with the outer surfaces of the strap legs 12 and 13, and the main portion of said legs 21 and 22 extend below the plane in which the strap flanges 15 and 16 lie. As is illustrated in Figure 4, the connection of a leg of the staple 20 in the opening 17 of the strap flange is an arrangement 100 105 110

whereby the staple leg might become detached with respect to the strap flange. However, in the assemblage of the staple and strap members, the staple legs 21 and 22 are provided on opposite sides with the upper crimps 25 and 26 upon diametrically opposed sides thereof, by means of any approved crimping tool to provide projections 27 and 28 respectively, overlying the top surfaces of the flanges 15 and 16. In order to permanently and securely attach the strap member 10 to the staple 20, the lower crimps 29 and 30 are provided in the legs 21 and 22 of the staple member 20 at diametrically opposed points in order to respectively provide the projections 31 and 32 which engage the under surface of the strap flanges 15 and 16. The crimps are arranged in the staple legs so that each leg has four projections or lugs therein, two upper lugs, and two lower lugs, to securely and permanently attach the flange through which said leg is disposed.

From the foregoing description of this invention, it can be seen that a compact and simple retaining device has been provided, which is particularly well adapted for use in connection with the supporting and mounting of armored cables; "Greenfield" metal flexible conduits; pipes; wires; moulding and other devices. Heretofore staples have been employed, which injure flexible cables and do not provide an effective retaining arrangement due to the limited surface of pipe or conduit which the same may engage. Also straps individually have been employed, but which take considerable time for the attachment of the same, in view of the fact that a plurality of retaining nails or staples have to be employed therewith, which are of course detachable with respect to the strap devices, so that considerable time is employed in securing the same to a support. By the provision of the perma-

~~BEST AVAILABLE COPY~~ 45
nently attached staple and strap members embodied in this invention, a retaining device has been provided which engages the cable or conduit to be supported over a relatively broad surface, and which may be attached without liability of injury to the strap detail of the retaining device, merely by a few blows of a hammer. In this manner, the retaining device may be quickly and conveniently arranged along a cable or conduit to be supported in an economical manner, without liability of injury to the cable, conduit, or the surface upon which the same is to be supported.

Various changes in the shape, size and arrangement of parts, may be made to the form of invention herein shown and described, without departing from the spirit of this invention or the scope of the claims.

I claim:

1. A retaining device comprising a rigid U-shaped clip having outwardly extending feet provided with fastener receiving cutouts, and a U-shaped staple straddling said clip and fitting in close engagement therewith, the arms of the staple being passed through the cutouts in the feet of the clip, the arms of the staple being rigidly secured to the feet to retain the clip and staple in engagement with each other and prevent independent movement thereof.

2. A retaining device comprising a U-shaped clip having its arms provided with outwardly extending feet, and a U-shaped staple straddling the clip in close contact therewith and having its arms extending through the feet of the clip, portions of the arms of the staple above and below the feet being crimped to provide portions engaging the upper and lower surfaces of the feet and firmly hold the staple in rigid engagement with the clip.

RAY S. ENGLE.
